UNITED STATES PATENT OFFICE

MAX C. MILLER, OF CUMBERLAND, RHODE ISLAND

KNITTING MACHINE

Original application filed April 10, 1923, Serial No. 631,071. Divided and this application filed March 7, 1931. Serial No. 520,810.

The invention relates to knitting machines, and more particularly to means for pressing the needles of an independent spring needle machine, being a division of the applicant's 8 Patent No. 1,809,057, dated June 9, 1931, for knitting machines.

The object of the invention is to provide a novel and improved means for pressing the needles of a spring needle machine which will 10 act with greater certainty than pressing devices previously developed, to engage and press the beard of the needles in a uniform manner regardless of any imperfections in or displacement of individual needles. With 15 this and other objects in view, the several features of the invention consist in the devices, combinations and arrangements of parts hereinafter described, which together with the advantages to be obtained thereby 20 will be readily understood by one skilled in the art from the following description taken in connection with the accompanying drawing.

In the drawing, Fig. 1 is a sectional view 25 of a needle cylinder illustrating the cooperative arrangement of the spring needle, presser, sinker and web holder; Fig. 2 is a diagrammatic plan view showing diagrammatically the arrangement of the presser 30 slides which press the beards of the needles and one of the presser actuating cams; Figs. 3 and 4 are perspective views showing two adjacent presser slides; and Fig. 5 is a detail view showing the overlapping needle engaging 35 faces of the needle pressers.

The drawing illustrates only so much of the machine as is necessary to show the connection of the present invention herewith.

As shown in the drawing the spring needles 40 2 are mounted in grooves in the needle cylinder 4 which may be rotated and oscillated by any suitable mechanism such as is usually employed for rotating and oscillating the needle cylinder of a seamless hosiery machine. 45 Each needle is actuated and controlled by a

jack 6, the upper end of which is recessed to receive the hook-shaped bent lower end of the needle so that the needle may be advanced and retracted by lengthwise movement of the jack and so that the jack may be swung radially inward and outward about the lower end of the needle to render the corresponding needle inactive or active. Each jack is provided with two outwardly projecting butts 8 and 10 for engaging the knitting cams which advance and retract the needs. The jacks are normally held with their butts projecting from the needle grooves into position to be acted upon by the knitting cams by sliders 12 mounted in the needle grooves and provided at their upper ends with forwardly extending projections 14 underlying guiding surfaces 16 on the inner sides of the jacks which are of sufficient length to remain in engagement with the projections 14 during the forward and retracting movements of the jacks and needles. Below the projections 14 each slider is cut away or recessed at 18 to permit the lower end of the jack to swing inward when the projection 14 is caused to register with the recess 20 formed in the back of the jack beyond the upper end of the guiding surface 16. Near the lower end of the recess 18 the slider is provided with a cam surface 22 arranged to engage the inclined lower end of the jack when the projection 14 registers with the recess 20 and acting to positively swing the lower end of the jack radially inward to remove the butt 8 of the jack from active relation to the cams which normally act thereon while permitting the butt 10 of the jack to remain in active projecting position. The jack and needle controlling sliders 12 are provided near their lower ends with projecting butts 24 arranged to be engaged and acted upon by controlling cams and devices, the sliders corresponding to the instep needles being provided with long butts while the sliders corresponding to the needles which

are operated in knitting the heel and toe are provided with short butts.

The radially movable web holders 56 and sinkers 58 are mounted in grooves in a dial 60 secured to the upper end of the needle cylinder and these web holders and sinkers, as well as the radially movable pressers to be described, are provided with short and long butts corresponding to the short and long butts of the needle controlling sliders 12 for the purpose of rendering inactive that series of these knitting elements which corresponds to the instep needles so that the instep needles which are partially up during the knitting of the heel or toe will not have yarn kinked about them or be pressed or have the loops of the fabric held thereby strained by the web holders. These knitting elements may be rendered active and inactive by cams corresponding to the cams which act on the butts of the needle controlling sliders 12.

The relative movements of the needles, web holders, sinkers and pressers to form the knitting wave, and the construction and operation of the cams for actuating these elements are fully illustrated and described in the applicant's copending application above referred to.

The means for pressing the beards of the needles which forms the principal feature of the present invention comprises a series of radially movable pressers, the beard engaging portions of which overlap to form a continuous pressing surface movable toward and from the needles. As shown the pressing means consists of a series of sliders 62 mounted in the grooves of the dial 60 above the web holders 56 and below the sinker 58. The presser sliders are provided at their outer ends with upwardly projecting butts, the instep pressers having long butts and the pressers which are active during the knitting of the heel and toe having short butts. The needle pressers are advanced to press the needles by cams, one of which is indicated at 64 in Fig. 2, these cams being arranged to engage both the long and short butts. The pressers are retracted by the corresponding sinkers, the forward ends of which are provided with depending portions 66 arranged to engage the forward ends of the pressers during the backward movement of the sinkers. The inner or needle engaging ends of the pressers are bent at right angles to the sliding portions to form overlapping needle engaging surfaces which are preferably curved to conform to the needle circle. Alternate pressers (Fig. 4) have their laterally bent ends arranged above and overlying the laterally bent ends (Fig. 3) of the intermediate pressers. The overlapping needle engaging surfaces of the pressers thus form a continuous pressing surface, as indicated in Fig. 5, surrounding the needles and this surface is moved into and out of engagement with the beards of the

needles by the forward and return movement of the individual pressers. With this construction the danger of mispressing due to the deflection of any needle slightly out of line with the corresponding presser is avoided and the proper and uniform pressing of the needle beards throughout the knitting is insured. The cams for advancing the pressers are arranged to advance the pressers after the needles have been drawn down to the pressing point and before the downward movement of the needles is continued by the stitch cam as more fully illustrated in the copending application above referred to. The pressers remain in advanced position until the sinkers are withdrawn when the downwardly projecting end 66 of the sinkers act against the inner ends of the pressers to withdraw them to inactive position.

The cams for operating and controlling the sinkers and pressers are carried by a stationary cam ring or support 68 and are arranged to operate upon the upwardly projecting butts of these knitting elements. The cams for operating and controlling the web holders are mounted on a cam ring 70 underlying the web holders, and these cams are arranged to engage the downwardly projecting butts of the web holders. The cams for advancing and retracting the web holders are preferably so arranged that the web holders after being withdrawn at the point where the active stitch cam draws the needles to the stitch level are not again advanced until the point is reached where the needles are advanced by the active needle advancing cam, thereby avoiding subjecting the loops held by the needles which are at the normal level between these points to unnecessary strain. This is permissible since the needles after passing the active stitch cam are not raised sufficiently to require the web holders to be moved inward until they reach the active needle advancing cams, but remain at an idle level only slightly above the level to which they are drawn by the active stitch cam.

While the invention has been shown and described as applied to a circular machine in which the needles are mounted to move vertically in the grooves of a needle cylinder it will be understood that it is not confined in its application to a machine of this character but may be embodied in machines having other forms of needle supports, and that the broader features of the invention may be applied to other types of machines.

What is claimed is:

1. In a knitting machine, a series of spring needles, and a corresponding series of reciprocating pressers provided with laterally projecting and overlapping beard pressing surfaces.
2. In a knitting machine, a circular series of spring needles and a corresponding circular series of independently movable press-

ers in front of the needles provided with overlapping beard pressing surfaces.

3. In a knitting machine, a circular series of spring needles, a corresponding series of sliding pressers mounted in front of the needle series and provided with laterally bent and overlapping forward ends for pressing the beards of the needles.

4. In a knitting machine, a series of independently movable spring needles, and a corresponding series of independently movable pressers provided with laterally projecting and overlapping beard pressing surfaces.
